DRIVE FOR PRINTING PRESSES AND OTHER MACHINES

Cyril P. Feldhausen, Wauwatosa, Wis., assignor to Cutler-Hammer, Inc., Milwaukee, Wis., a corporation of Delaware

Application March 31, 1939, Serial No. 265,155

15 Claims. (Cl. 172—239)

This invention relates to improvements in drives of the two motor type for printing presses and other machines.

For printing press drive it has been found very advantageous to employ a double motor drive comprising a large motor for running, and a small motor for starting, inching and operating the press at threading speed. In such drives it has been the common practice to employ an over-running clutch to enable the large motor to take over the drive while the small motor is operating and to free the small motor upon overrunning by the large motor. This type of drive is very satisfactory for drive of the press in a single direction but there is now a demand for reversibility of the two motor drive and use of an over-running clutch presents difficulties.

The present invention has among its objects to provide a simple and highly satisfactory two motor drive having reversibility and the advantages of the aforementioned drive, the eliminating need of an over-running clutch.

Another object of the invention is to provide a two-motor drive wherein reversibility is enabled through the use of an electromagnetic clutch in lieu of the heretofore employed over-running clutch.

Another object of the invention is to provide a two-motor drive wherein one or both motors may be provided with individual brakes or the large motor may be braked through the medium of the aforementioned electromagnetic clutch, assuming the small motor to be prevented from rotating.

Another object is to afford through use of an electromagnetic clutch transfer of the drive from one motor to the other smoothly, without undue shock to the driven machine.

Various other objects and advantages of the invention will hereinafter appear.

Certain embodiments of the invention are illustrated in the accompanying drawing which will now be described, it being understood that the embodiments illustrated are susceptible of modification without departing from the scope of the appended claims.

In the drawing,

Figure 1 is a more or less schematic view of a driving mechanism wherein the two motors are arranged to be fixed to a common support;

Fig. 2 is a more or less schematic view showing a modification of Fig. 1;

Fig. 3 is a more or less schematic view showing the small motor mounted upon and above the large motor;

Fig. 4 is a more or less schematic view showing the small motor supported by the large motor with the armatures of said motors axially aligned;

Fig. 5 is a diagrammatic view showing power connections for the two motors, and

Figs. 6, 7 and 8 are diagrammatic views showing with certain variations control means for the two motors, and the magnetic clutch associated with said motors.

Referring to Fig. 1, the same shows a large motor M and a small motor M¹ which in practice might be mounted on a common base. The large motor has a shaft extension 1 to be connected to the press or other driven machine in any preferred manner as by a chain drive. The opposite end of the shaft of the large motor is connected through an electromagnetic clutch C to a gear 2 meshing with a smaller gear 3 carried by an intermediate shaft 4. The shaft 4 has mounted thereon and coupled to gear 3 a gear 5 meshing with a smaller gear 6 on the shaft of small motor M¹.

The electromagnetic clutch C may be of any one of a number of well known types, being preferably of the friction disk type energizable for clutching and deenergizable for release. Assuming use of such a clutch when it is energized it affords a drive from the small motor M¹ through the aforesaid gearing and clutch to the shaft of the motor M and through the extension 1 of said shaft to the press or other driven machine. On the other hand, when the clutch C is deenergized the drive from the small motor is interrupted, leaving only the large motor M connected to the press or other driven machine.

The small motor as in the ordinary drive preferably is designed for starting under the load of the press or other machine and after transfer of the load to the large motor the small motor preferably is disconnected from circuit. When the large motor is driving, the load may be re-transferred to the small motor by bringing the large motor to a suitable speed, and then disconnecting the large motor from circuit, at the same time energizing the clutch C. In transfer of the load from one motor to the other the slippage of the clutch will tend to eliminate the shocks, if any, to the driven machine due to difference in speed of the parts driven by the two motors.

Further referring to Fig. 1, the same schematically shows brakes B and B¹ for the large and small motors, respectively. These brakes may be of any preferred type and controlled in any preferred manner. If the large motor is of a type

adapted to be plugged then plugging may be employed in lieu of brake B. Furthermore the brake B may be dispensed with and braking of the motor M may be effected by braking the small motor M¹ and energizing clutch C. The clutch C will then gradually brake the motor through friction of the engaging parts which initially will slip.

Referring to Fig. 2, the same shows the clutch C mounted on extension 1 of the large motor shaft. The clutch has its field member c¹ fixed to the shaft, and its armature member c² fixed to the gear 2, said gear in turn having a bearing on the bell of the motor.

Referring to Fig. 3, the large motor M is provided with a bracket 8 to support the small motor M¹ and the clutch C is mounted on the shaft of the large motor, being provided with a pulley 9 connected through a driving belt 9^a to a pulley 10 provided on the shaft of the small motor. This arrangement wherein the small motor is mounted on and above the large motor is particularly advantageous where economy of floor space is important.

Referring to Fig. 4, the large motor M is provided with a bracket 11 on which the small motor M¹ is mounted in axial alignment with the large motor. In this case it is assumed that the small motor is of a geared head type, the clutch C constituting a direct coupling for the shaft of the large motor and the small motor.

It is to be understood that the motors may be of any preferred type, either D. C. or A. C. However, for simplicity of illustration of the power connections (Fig. 5) use of D. C. motors is assumed. Referring to Fig. 5, the motor M is illustrated as comprising an armature A and a series field winding F, while the motor M¹ is illustrated as comprising an armature a and a series field winding f. Reversing switches 12 and 13 are provided for the armatures a and A respectively. While the reversing switches 12 and 13 are shown as of the knife switch type it is to be understood that any other preferred type of reversing switches either manual or power operated may be substituted therefor. Also Fig. 5 shows the circuit of motor M¹ provided with an electroresponsive main switch 14 and the circuit of motor M provided with an electroresponsive main switch 15 having normally closed auxiliary contacts 15^b for a purpose hereinafter set forth. As illustrated the motors are reversible independently of one another, but it is of course to be understood that if desired provision may be made whereby reversal of either motor effects reversal of the other motor. In this figure the small motor brake B¹ is depicted as a winding, assumed to be a brake releasing winding, having means to connect it across armature a.

Referring to Fig. 6, the same shows how the control of the two motors and the electromagnetic clutch may be accomplished in a very satisfactory manner by the crosshead type of controller extensively used for printing press control. For simplicity of illustration many details of the standard crosshead type of controller have been omitted from Fig. 6, and for further simplification certain switches are given more direct control of other switches illustrated than in the standard controller. However, the showing of Fig. 6 will serve clearly to indicate to workers in the art how control of the motors and the clutch readily may be incorporated in the standard controller for obtaining all advantages

thereof. Fig. 6 shows the windings 14^a and 15^a of the small motor main switch 14 and the large motor main switch 15, respectively, the winding c of the clutch C, a motor driven crosshead type controller 20, a "stop" relay 21, an "inch" relay 22, a clutch relay 23, relays 24 and 25 to control the motor driven rheostat and certain push button control switches hereinafter specified.

The crosshead type controller 20 is only shown in part, only the contacts thereof employed to control the continuity of circuit of the motors being illustrated. As will be understood, the crosshead in practice is additionally provided with contacts affording a wide range of speed control of the large motor and speed control of the small motor if desired. As illustrated the controller 20 comprises a crosshead 30, a series of contact buttons 31 aligned with contact strip 32 and a second smaller group of contact buttons 33 aligned with contact segment 34. As illustrated the buttons 33 are not connected together and have no connection with the strip 34, whereas the left hand first two buttons of the series 31 are disconnected from one another and from the remaining buttons. The next four buttons 31 are interconnected but disconnected from the remaining buttons, and the last two buttons 31 are interconnected and connected to strip 32. The strip 32 is connected to one terminal of the winding 15^a of the large motor main switch, while the intermediate interconnected buttons 31 are connected to one terminal of the winding 14^a of the small motor main switch. The extreme left hand button 31 is connected to line L¹ through a push button switch 35, while the extreme left hand button 33 is connected to one terminal of the winding of the "inch" relay 22. When crosshead 30 is in the position illustrated it enables energization of the inch relay 22 which upon closing completes a circuit from line L¹ to a terminal of the winding 14^a of the small motor main switch in shunt with the crosshead controller. On the other hand, when the crosshead moves to the right to bridge strip 34 with the first of the intermediate interconnected buttons 31 it completes a circuit from line L¹ to the winding 14^a of the small motor main switch in parallel to the aforementioned circuit established by the "inch" relay. Continued movement of the crosshead to the right maintains the circuit of the winding of the small motor main switch until said crosshead reaches the buttons 31 connected to strip 32 whereupon said crosshead completes circuit from line L¹ to the winding 15^a of the large motor main switch. Upon continued movement of the crosshead to the right it interrupts the circuit of the winding 14^a while maintaining the circuit of the winding 15^a of the large motor main switch.

Such operation of the crosshead 30 is effected through the medium of a pilot motor shown as comprising an armature 36 and oppositely wound series field windings 37 and 38 to be included in circuit selectively. The aforementioned relay 24 when energized connects across lines L¹ and L² the armature 36 and the field winding 37 for operation of the crosshead 30 in one direction, assumed to be to the "off" direction, while relay 25 when energized connects across lines L¹ and L² the armature 36 and the field winding 38 for operation of the crosshead in a reverse direction, assumed to be "on" direction. The windings of the relays 24 and 25 are in turn respectively controlled by push button switches 39 and 40.

Considering the controller thus far described, it

will be seen that with the crosshead 30 in the position shown the small motor M¹ may be started by depressing the push button switch 35 which is effective only in such position of the crosshead. On the other hand, the crosshead may be adjusted through depression of the "on" button to establish the independent circuit for the winding of the small motor main switch and thereafter to establish circuit for the winding of the large motor main switch. The crosshead may be arrested on the intermediate buttons 31 by release of the "on" push button switch for continuous operation of the small motor pending return of the crosshead to the position shown by depression of the "off" push button switch to start and move the crosshead to the left or deenergization of the small motor main switch otherwise as herein-after explained. Similarly depression of the "off" push button switch 39 provides for return of the crosshead when positioned to energize the winding of the large motor main switch, the return movement energizing the winding of the small motor main switch while the crosshead engages the intermediate interconnected contacts 31.

The "stop" relay has normally open contacts 21^a, 21^b and 21^c and normally closed contacts 21^d. Contacts 21^a are in circuit with the winding of "inch" relay 22. Contacts 21^b are included in the common connection between line L² and the windings of the main switches 14 and 15 of the small motor and the large motor respectively. Contacts 21^c are included in circuit with the winding of "on" relay 25. Thus when the "stop" relay 21 is deenergized it provides for immediate stopping irrespective of the position of the crosshead by deenergizing the main switches, and further provides for deenergization of the "inch" relay if energized and for deenergization of the "on" relay if energized. On the other hand, deenergization of the "stop" relay engages its contacts 21^d which are in circuit with the winding of "off" relay 24, thereby effecting return of the crosshead to initial position where it is arrested by a limit switch 41. A limit switch 42 arrests the crosshead when driven to its other limit. The winding of "stop" relay is adapted to be connected across lines L¹ and L² by a push button switch 43 to be closed for running and opened for stopping, said switch being adapted to remain in either open or closed position without manual retention.

The large motor main switch 15 has its normally closed contacts 15^b in circuit with the winding of clutch relay 23. The contacts 15^b when closed connect the winding of the clutch relay 23 across the lines, causing said relay to respond to connect the clutch coil c across the lines. On the other hand, opening of contacts 15^b deenergizes the clutch relay 23 to disconnect the clutch coil c from circuit.

With such circuit connections for the clutch coil c it will be apparent that with the motors at rest the clutch relay is energized to energize the clutch coil at the time starting is effected whether through the medium of the inching means or the "on" means. Thus at the instant of starting the small motor said motor is connected to the press or other driven machine. On the other hand, it will be observed that when the large motor is started to take over the drive of the press or other machine the contacts 15^b of its main switch will deenergize the clutch relay to deenergize the clutch coil, thereby freeing the small motor. Also it will be observed that upon return of the crosshead to transfer the load from

the large motor to the small motor the contacts 15^b of the large motor main switch will reclose to again energize the clutch relay and thereby again energize the clutch coil c.

The control of the brake B of Fig. 1 is not illustrated, as its control is well understood. If the brake B is employed its controlling medium may, if desired, be provided with contacts in circuit with the winding of the clutch relay 23 to necessitate release of the brake for energization of said clutch relay.

On the other hand, if the brake B for the large motor is not employed the system of Figs. 5 and 6 will afford braking of the large motor through the clutch when the large motor is stopped through deenergization of the "stop" relay. As hereinbefore explained deenergization of the "stop" relay deenergizes the large motor main switch and also the small motor main switch if energized. Deenergization of the main switch 15 energizes the clutch as hereinbefore explained, and as will appear from Fig. 5 main switch 14 disconnects the coil of brake B¹ of the small motor. Thus the small motor brake sets and the small motor brakes the large motor through the clutch.

Where use of the clutch for braking is not desired the clutch circuit preferably is modified as shown in Fig. 7. In this instance the energizing circuit of the clutch relay 23 includes in addition to contacts 15^b of Fig. 6 contacts 14^c and 24^b connected in parallel and connected in series with contacts 15^b. Contacts 14^c are assumed to be normally open contacts of the small motor main switch 14, while contacts 24^b are assumed to be normally closed contacts of "off" relay 24. Thus the clutch relay is rendered unresponsive to opening of the large motor main switch except when the small motor main switch has been closed for restarting the small motor or the "off" relay has been deenergized after returning the crosshead to initial position in preparation for again starting the drive.

If it be desired to start the small motor slightly in advance of engagement of clutch C instead of after engagement of the clutch as in Fig. 6 this can readily be accomplished by the modification shown in Fig. 8. In Fig. 8 the energizing circuit of clutch relay 23 includes in addition to the large motor main switch contacts 14^b and in series therewith contacts 14^d assumed to be normally open contacts of the small motor main switch 14. With this arrangement the clutch relay is energized to energize the clutch only when the large motor main switch is open and only when the small motor main switch has responded to start the small motor.

What I claim as new and desire to secure by Letters Patent is:

1. For printing presses and other machines, in combination, a driving motor for operation of the driven machine through a given speed range, a smaller driving motor for starting the driven machine and for slow speed operation thereof, control means for said motors providing for starting always by said smaller motor and including reversing means for said smaller motor and driving connections from said motors to the driven machine in part common to both motors and including a releasable connection through which said smaller motor drives, said releasable connection serving to transmit power from said smaller motor upon operation of the latter in either direction and having control means effecting its release as an incident to starting of the other of said motors.

2. For printing presses and other machines, in combination, a driving motor for operation of the driven machine through a given speed range, a smaller motor for starting of the driven machine and for slow speed operation thereof, control means for said motors providing for starting always by said smaller motor and including reversing means for said motors, and driving connections from said motors to the driven machine in part common to both motors and including an electromagnetic clutch through the medium of which drive from said smaller motor may be established and interrupted regardless of the direction of operation of said motors, said control means also including means for transferring the drive from either motor to the other by effecting operation of both motors for at least a brief period and release or engagement of said clutch according to whether the transfer is from the smaller motor to the larger motor or vice versa and said control means protecting against power drive by both motors simultaneously.

3. For printing presses and other machines, in combination, a driving motor for operation of the driven machine through a given speed range, a smaller motor for starting of the driven machine and for slow speed operation thereof, control means including reversing means for said motors, and driving connections from said motors to the driven machine in part common to said motors and including an electromagnetic clutch through the medium of which drive from said smaller motor may be established and interrupted regardless of the direction of operation of said motors, said control means also including means to effect starting of said smaller motor with said clutch engaged and subsequent starting of the other motor while said smaller motor is in operation, effecting disengagement of said clutch to free said smaller motor upon initiation of starting of said other motor.

4. For printing presses and other machines, in combination, a driving motor for operation of the driven machine through a given speed range, a smaller motor for starting of the driven machine and for slow speed operation thereof, control means including reversing means for said motors and driving connections from said motors to the driven machine in part common to said motors and including an electromagnetic clutch through the medium of which drive from said smaller motor may be established and interrupted regardless of the direction of operation of said motors, said control means including means to effect drive of the driven machine by said smaller motor through said clutch and transfer of the drive from said smaller motor to the other of said motors, releasing said clutch for disconnection of said smaller motor as an incident to starting of the other of said motors, and thereafter to effect transfer of the load back to said smaller motor through reengagement of said clutch with said smaller motor in operation.

5. For printing presses and other machines, in combination, a two motor drive comprising a relatively small motor and a larger motor, an electromagnetic clutch for coupling said small motor to the shaft of said larger motor to drive the driven machine through said shaft, and control means for said motors and clutch including reversing means for both motors and also including means first to effect starting of said small motor and engagement of said clutch and thereafter to start said larger motor while said small motor is in operation and to disengage said clutch,

said last mentioned means also affording simultaneous operation of said motors and re-engagement of said clutch as an incident to interrupting the power supply to said larger motor for transferring the load back to said small motor.

6. For printing presses and other machines, in combination, a two motor drive comprising a relatively small motor and a larger motor, an electromagnetic clutch for coupling said small motor to the shaft of said larger motor to drive the driven machine through said shaft, and control means for said motors and clutch including reversing means for both motors and also including means first to effect starting of said small motor and engagement of said clutch and then to start said larger motor while said small motor is in operation and to disengage said clutch immediately upon establishment of power supply for said larger motor said last mentioned means insuring engagement of said clutch at the time said small motor is started.

7. For printing presses and other machines, in combination, a two motor drive comprising a relatively small motor and a larger motor, an electromagnetic clutch for coupling said small motor to the shaft of said larger motor to drive the driven machine through said shaft, and control means for said motors operable first to start said small motor, thereafter during operation of said small motor to start said larger motor, stopping said smaller motor and thereafter to restart said smaller motor, stopping said larger motor, said means controlling said clutch for engagement thereof when only said small motor is operating, for disengagement of said clutch upon starting of said larger motor and for re-engagement of said clutch upon stopping of said larger motor.

8. For printing presses and other machines, in combination, a two motor drive comprising a relatively small motor and a larger motor, an electromagnetic clutch for coupling said small motor to the shaft of said larger motor to drive the driven machine through said shaft, and control means for said motors and clutch including reversing means for both motors and also including means operable to effect in sequence starting of said small motor, starting of said larger motor while said small motor continues to operate, stopping and restarting said small motor while said larger motor continues to operate, and stopping of said larger motor, said last mentioned means controlling said clutch for engagement thereof when only small motor is operating, for disengagement of said clutch simultaneously with starting of said larger motor and for re-engagement of said clutch when said larger motor is disconnected from circuit with said small motor in operation.

9. For printing presses and other machines, in combination, a two motor drive, comprising a relatively small motor and a larger motor, an electromagnetically engaged friction clutch for coupling said small motor to the shaft of said larger motor to drive the driven machine through said shaft, and control means for said motors and clutch including reversing means for both motors and also including means to effect operation of said motors selectively, starting the larger motor prior to stopping the small motor and vice versa, and at substantially the same time effecting disengagement or re-engagement of said clutch according to whether the transfer of load is from the small motor to the larger motor or vice versa.

10. For printing presses and other machines,

in combination, a two motor drive comprising a relatively small motor and a larger motor, an electromagnetic friction clutch for coupling said small motor to the shaft of said larger motor to drive the driven machine through said shaft, and control means for said motors operable first to start said small motor, thereafter during operation of said small motor to start said larger motor, stopping said small motor and thereafter to restart said small motor while said larger motor continues to operate and then stopping said larger motor, said means controlling said clutch for engagement thereof when only said small motor is operating, and for disengagement of said clutch upon starting of said larger motor and until the power supply to said larger motor is terminated.

11. For printing presses and other machines, in combination, a two motor drive comprising a relatively small motor and a larger motor, an electromagnetically controlled friction clutch for coupling said small motor to the shaft of said larger motor to drive the driven machine through said shaft, a brake for said small motor and control means for said motors, said clutch and said brake to effect drive of the driven machine through said clutch by said small motor and to effect operation of said larger motor and disengagement of said clutch for transfer of the drive from said small motor to said larger motor, said control means providing for setting of said brake of said small motor and for re-engagement of said clutch to brake said larger motor.

12. For printing presses and other machines, in combination, a two motor drive comprising a relatively small motor and a larger motor, an electromagnetically controlled friction clutch for coupling said small motor to the shaft of said larger motor to drive the driven machine through said shaft, a brake for said small motor and control means for said motors, said clutch and said brake to effect drive of the driven machine through said clutch by said small motor and to effect operation of said larger motor and disengagement of said clutch for transfer of the drive from said small motor to said larger motor, said control means including reversing means for both motors and means to effect setting of said brake of said small motor and re-en-

gagement of said clutch to brake said larger motor.

13. For printing presses and other machines, in combination, a relatively small driving motor, a larger driving motor, driving connections from said motor to the driven machine in part common to both of said motors, said connections including a releasable connection for said small motor, which releasable connection serves to transmit power from said small motor upon operation of the latter in either direction, and control means for said motors and said connection including reversing means for said small motor, means for effecting operation of said motors selectively or simultaneously and for controlling said releasable connection for transfer of the drive from said small motor to said larger motor or vice versa, while protecting against power drive by both motors simultaneously.

14. For printing presses and other machines, in combination, a two motor drive comprising a relatively small motor and a larger motor, driving connections from said motors to the driven machine, the driving connections from said small motor including an electromagnetic friction clutch, and control means for said motors and said clutch operable first to start said small motor with said clutch disengaged and said larger motor idle, then to engage said clutch and then to start said larger motor for drive of the machine disengaging said clutch as an incident to establishing power supply to said larger motor.

15. For printing presses and other machines, in combination, a relatively small driving motor, a larger driving motor, driving connections from said motors to the driven machine including a releasable connection for said small motor which mechanically connects said small motor and said larger motor and which when released interrupts the drive from said small motor, a brake for said small motor, and control means for said motors, said releasable connection and said brake, and said control means effecting drive of the driven machine by said motors selectively and braking of said larger motor by mechanically connecting said motors through said releasable connection and applying said brake to said small motor.

CYRIL P. FELDHAUSEN.

CERTIFICATE OF CORRECTION.

Patent No. 2,252,762.

August 19, 1941.

CYRIL P. FELDHAUSEN.

It is hereby certified that error appears in the printed specification of the above numbered patent requiring correction as follows: Page 1, first column, line 21, for "the" read --but--; page 3, second column, line 49, for "contacts 14^b" read --contacts 15^b--; and that the said Letters Patent should be read with this correction therein that the same may conform to the record of the case in the Patent Office.

Signed and sealed this 28th day of April, A. D. 1942.

(Seal)

Henry Van Arsdale,
Acting Commissioner of Patents.
